UNITED STATES PATENT OFFICE.

EDWIN B. BULLOCK, OF ATTLEBOROUGH, MASSACHUSETTS.

DESIGN FOR A GARTER.

SPECIFICATION forming part of Design No. 31,488, dated August 29, 1899.

Application filed June 26, 1899. Serial No. 721,968. Term of patent 7 years.

To all whom it may concern:

Be it known that I, EDWIN B. BULLOCK, of Attleborough, in the county of Bristol and State of Massachusetts, have invented and 5 produced a new and original Design for Garters, of which the following is a specification, reference being had to the accompanying drawing, forming part thereof.

The drawing represents a view of a garter 10 illustrating my new design.

The leading feature of my new and original design for garters consists in the design as herein shown and described.

As shown in the drawing, the straight band 15 5 has the ornamental ends 6 6', each of which has the edge curves 6' 6' meeting at the point 6'', having also surface ornaments consisting

of the scrolls 6³ 6³. Between these ends are the ornaments 7 7, the edge pieces 8 8 of which are connected by the bars 9 and 10 crossing 20 the band 5 and exposing the material of the same to view between the bars. The bars 10 have the curved shoulders 10' 10', from which the outline curves inward and then outward to the point 10'', the surface ornamentation 25 of the bars 10 consisting of the surface scrolls 10³ 10³.

What I claim is—

The design for a garter as herein shown and described.

EDWIN B. BULLOCK.
